UNITED STATES PATENT OFFICE.

WINFIELD C. SECKLER, OF MARIANNA, ARKANSAS.

MAGAZINE-CAMERA.

No. 892,903.

Specification of Letters Patent.

Patented July 7, 1908.

Application filed July 11, 1907. Serial No. 383,293.

To all whom it may concern:

Be it known that I, WINFIELD C. SECKLER, a citizen of the United States, residing at Marianna, in the county of Lee and State of Arkansas, have invented a new and useful Magazine-Camera, of which the following is a specification.

This invention relates to photographic apparatus and more particularly to cameras for producing tintypes.

The object of the invention is to provide a magazine camera of this character having novel mechanism whereby plates can be successively placed in proper position in rear of the lens and subsequently discharged into a developing bath provided for them.

A still further object is to provide pneumatically operated means for actuating both the feeding mechanism and the shutter.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a vertical longitudinal section through the apparatus, one of the positions of the feed mechanism being shown by dotted lines. Fig. 2 is a similar section through the hopper of the feed mechanism and showing the conveyer of said mechanism in the position assumed thereby upon depositing a plate within the hopper. Fig. 3 is a section on line 3—3, Fig. 2. Fig. 4 is a detail view of the magnet used in connection with the apparatus.

Referring to the figures by characters of reference, 1 designates a suitable casing having a transversely extending horizontal partition 2 forming an upper compartment 3 and a lower compartment 4. The lens tube 5 is mounted within the casing and the shutter 6, which may be of any form designed to be actuated by the compression of a bulb, is located within the casing and directly in rear of said tube. Supported within the compartment 3 and above the partition 2 is a platform 7 supporting a trough 8 having an inclined bottom at the upper end of which is disposed a hopper 9 having an upright wall extending downward below the hopper and through the outlet opening 10 in partition 2. This upright wall 11 forms part of a chute 12 designed to direct into the opening 10 the plates which are successively supplied to the

hopper as hereinafter stated. Apertures 13 are formed within the wall 11 near its lower end and extending from said wall close to and below the openings are supporting fingers 14. Projecting loosely into the openings 13 are the ends of a fork 15 formed at one end of a releasing bar 16. This bar is pivoted within the platform 7 and pivotally connected to its upper end is a push bar 17 which has a forked end normally resting upon the upper end of wall 11. Spring strips 18 preferably angular in form project from the forked end of the push bar 17 and are spaced apart as shown particularly in Fig. 3. These springs constitute stop devices and are for the purpose hereinafter set forth.

A suitable supporting frame 19 is mounted on the platform 7 and extending upward therefrom are standards 20 in which are journaled trunnions 21 extending laterally from a tiltable member such as a cylinder 22. A piston 23 is mounted to reciprocate within the cylinder and has a stem 24 movable therewith and projecting beyond one end of the cylinder, said stem carrying a horseshoe magnet 25. A stripping plate 26 is connected to the cylinder 22 by means of a strip 27 and when the piston and magnet are in their normal positions said magnet straddles the strip 27 while the plate 26 projects beyond and below the magnet. The normal positions of these parts has been illustrated by full lines in Fig. 1. A compressible bulb 28 is connected by means of a main tube 29 and branch tubes 30 and 31 with one end of cylinder 22 and with the shutter respectively so that when the bulb is compressed the piston 23 and the shutter will be simultaneously actuated.

Guide cleats 32 are secured upon the lower face of the partition 2 and mounted between them and upon the bottom of casing 1 is a slide 33 having a pocket 34 in which is mounted a receptacle 35 designed to contain the developing fluid. When the slide is in its normal position this receptacle is located directly under the opening 10. A slide 36 is mounted upon the lower face of partition 2 and a spring 37 serves to hold the slide normally in position to close the opening 10. Said slide projects rearwardly from the casing 1 so that the same can be readily withdrawn from the opening by the operator. A door 38 is preferably provided for the purpose of closing the compartment 4. A cross bar 39 connects the sides of the slide at their

outer ends, and constitutes a grip by means of which the slide can be easily pulled out of the compartment 4. An opening 40 is formed in one wall of the casing 1 and secured therein is one end of a fabric tube 41 formed of a material which will exclude light. This tube normally hangs loosely within the compartment 3 as shown in Fig. 1.

It is to be understood that the shutter is normally closed and that the parts of the apparatus are normally in the positions shown in Fig. 1. A stack 42 of suitably prepared tin plates is placed within the trough 8 with their prepared surfaces downward and the device is then in condition for use. When the bulb 28 is compressed the shutter 6 is opened. At the same time air is forced back of the piston 23 and projects the stem 24 longitudinally as indicated by the dotted line in Fig. 1 until the cylinder is overbalanced whereupon the magnet 25 will swing downward onto the upper plate of the stack 42. The parts will remain in these positions until the bulb 28 is released. The bulb will then produce a sufficient suction to cause the shutter 6 to close and the piston 23 will be drawn quickly backward to its normal position. This will result in the magnet being drawn rearwardly into position shown in Fig. 2 and the upper plate of the stack 42 will of course cling to the magnet and be carried thereby into contact with the stripping plate 26. This stripping plate will detach the tin plate from the magnet and cause it to drop into the hopper 9 as shown by dotted lines in Fig. 1. Meanwhile the magnet 25 has struck the springs 18 and actuated the push bar 17. This causes the releasing bar 16 to swing into the openings 13 and force off of fingers 14 any plate which may have been supported thereby. The magnet 25 swings upward to its normal position as soon as it contacts with springs 18 and therefore the releasing bar promptly returns to its normal position so that the plate released from the magnet will be free to slide downward and be supported upon the fingers 14. When the bulb is again compressed the shutter is opened and the foregoing operation is repeated. Each time a plate is released from the fingers 14 it drops by gravity into the developing fluid. It is of course to be understood that the slide 36 should be withdrawn from opening 10 each time the bulb 28 is released.

It will be apparent that by providing mechanism such as described a large number of plates may be placed within the apparatus and successively used without requiring any attention other than the actuation of the bulb and the slide.

Should any part of the mechanism get out of order it can be readily reached by inserting an arm through the tube 41.

To prevent the plates wedging in the hopper while being delivered to the supporting

devices any supporting means, such as a guide plate 9^a, may be placed in the hopper to turn the plates so as to raise them to almost an upright position. Although this guiding device has been shown in the drawings as formed of a plate it is to be understood that the same may, if preferred, consist of a solid block of material although a plate is preferable because of its lightness and cheapness.

What is claimed is:

1. In apparatus of the character described the combination with a plate holder, and means for supporting a plate discharged from the holder; of a slidably and pivotally supported magnet, and means for shifting the magnet to overbalance and tilt the same to withdraw a plate from the holder.

2. In apparatus of the character described the combination with a plate holder, and means for supporting a plate subsequent to its withdrawal from the holder; of a slidably and pivotally supported magnet, and pneumatic means for shifting the magnet to overbalance and tilt the same to withdraw a plate from the holder.

3. In apparatus of the character described the combination with a plate holder, and means for supporting a plate subsequent to its removal from the holder; of a tilttable member, a reciprocating magnet movably connected thereto, pneumatic means for reciprocating the magnet to tilt said member and to withdraw a plate from the holder, and means in the path of the magnet for releasing a plate therefrom.

4. In apparatus of the character described the combination with a plate holder, and means for supporting a plate subsequent to its removal from the holder; of a tilttable reciprocating magnet, pneumatic means for actuating the magnet to withdraw a plate from the holder, and means in the path of the magnet and disposed to be actuated thereby to release a plate from its supporting means.

5. In apparatus of the character described the combination with a plate holder, and means for supporting a plate subsequent to its removal from the holder; of a tilttable reciprocating magnet, means for actuating the magnet to withdraw a plate from the holder, means for directing a plate from the magnet and onto the supporting means, means actuated by the magnet for releasing a plate from the supporting means.

6. In apparatus of the character described the combination with a plate holder, a developing bath, and means interposed between the holder and bath for supporting a plate above the bath; of a magnet, means for actuating the magnet to remove a plate from the holder, means for directing a plate onto the supporting means, and means operated by the magnet for releasing the plate from the supporting means.

7. In apparatus of the character described the combination with a plate holder, a bath, and means for supporting a plate between the holder and bath; of a magnet, means for actuating the magnet to withdraw a plate from the holder, means for directing a plate from the magnet onto the supporting means, and means operated by the magnet actuating means for releasing the plate from the supporting means.
8. In apparatus of the character described the combination with a plate holder, a bath, and means for supporting a plate between the holder and bath; of an air forcing device, and separate means actuated by said device for removing a plate from the holder, for directing it onto the supporting means, and for releasing it from the supporting means.
9. In apparatus of the character described the combination with a plate holder, a bath, a lens, and means for supporting a plate between the holder and bath in the focus of the lens; of air forcing means, and separate means actuated thereby for withdrawing a plate from the holder, for directing it upon the supporting means, for exposing the plate, and for releasing the plate from the holding means.
10. In apparatus of the character described the combination with a plate support; of pneumatically operated means for successively directing plates onto the support, and mechanism operated by said means for successively releasing the plates from the supports.
11. In apparatus of the character described the combination with a plate support and a hopper for directing plates thereonto; of means for successively directing plates into the hopper, and mechanism operated by said means for successively releasing the plates from the support.
12. In apparatus of the character described the combination with a plate support, a hopper for directing plates thereonto, and a plate holder; of a magnet, means for actuating the magnet to withdraw a plate from the holder, means for stripping a plate from the magnet and directing it into the hopper, and means operated by the magnet for successively releasing plates from the support.
13. In apparatus of the character described the combination with a plate holder; of a tilttable cylinder, a piston mounted therein, a magnet outside of the cylinder and movable with the piston, and means for directing pressure against the piston to direct the magnet into position above the holder, said magnet being disposed to overbalance the cylinder and to swing into the holder.
14. In apparatus of the character described the combination with a plate holder and a plate support; of a tilttable cylinder, a piston mounted to reciprocate therein, a magnet movable with the piston, means for directing a confined body of fluid against the piston to project the magnet and overbalance the cylinder, said magnet being disposed to move onto a plate within the holder, means in the path of the magnet and movable with the cylinder for detaching a plate from the magnet, means for directing a plate onto the support, and means in the path of and operated by the magnet for releasing the plate from the support.
15. In apparatus of the character described the combination with a lens, and means for supporting a plate within the focus of the lens; of a tilttable member, a magnet movably connected thereto, and means for shifting the magnet to overbalance the tilttable member and raise the magnet, said magnet being disposed when raised to direct a plate upon the supporting means.
16. In apparatus of the character described the combination with a lens, and means for supporting a plate within the focus of the lens; of a tilttable member, a magnet movably connected thereto, and means for shifting the magnet to overbalance the tilttable member and raise the magnet, said magnet being disposed when raised to convey a plate, and means in the path of the magnet for detaching plates therefrom and directing them upon the supporting means.

In testimony that I claim the foregoing as my own, I have hereto affixed my signature in the presence of two witnesses.
